THERAPEUTIC TRACTION APPLIANCE

Edward J. Treutelaar, 8439 W. Sunnyside,
Chicago, Ill. 60631

Filed Oct. 21, 1966, Ser. No. 4,371

Term of patent 7 years

(Cl. D83—1)

Fig. 1.

Fig. 2.

Fig. 3

FIG. 1 is a side perspective view of a therapeutic traction appliance showing my new design, the opposite side being substantially the same;

FIG. 2 is a rear perspective view of the opposite side thereof;

FIG. 3 is a front perspective view viewed from the top thereof.

I claim:

The ornamental design for a therapeutic traction appliance, as shown and described.
